United States Patent Office.

ABRAM CLOW, OF PORT BYRON, NEW YORK.

Letters Patent No. 79,207, dated June 23, 1868.

IMPROVEMENT IN THREAD-GUIDING PLATE FOR FILLING TATTING-SHUTTLES.

The Schedule referred to in these Letters Patent and making part of the same.

TO ALL WHOM IT MAY CONCERN:

Be it known that I, ABRAM CLOW, of Port Byron, in the county of Cayuga, and State of New York, have invented a new and improved Thread-Guide for Filling Shuttles; and I do hereby declare that the following is a full, clear, and exact description thereof, which will enable those skilled in the art to make and use the same, reference being had to the accompanying drawings, forming a part of this specification, in which—

Figure 1 is a face view of my invention, and

Figure 2 is a section of the same, taken in the line $z z$ in fig. 1.

Figure 3 is a perspective view of the shuttle.

Similar letters of reference indicate like parts.

This invention relates to a new and improved method of filling tatting-shuttles; and the invention consists in a slotted metal disk, so constructed as to receive the points of one side of the shuttle, and then present a suitable face for guiding the thread between the points of the shuttle, as hereinafter more fully explained.

In the accompanying drawings, A is a disk, of metal or other suitable material, having a slot, a , and an L-shaped slot, $b b'$, and also two raised parts, $c d$, which are struck up, so as to cover the points of the shuttle e , as shown in fig. 2, when said points have been passed through the slots $a b$. Two points, ff , are also cut out in the disk and bent backward, to serve as handles for holding the device when in use.

In placing the shuttle in the disk, one of its points is first introduced under the raised part c , and the opposite point is then placed behind the raised part d and in the slot $b b'$.

When the shuttle is placed in the disk, as seen in fig. 2, the thread can be wound on the shuttle with great rapidity, by carrying the thread so that it will follow the face $h h$ of the disk or guide.

The device is manufactured at a very light cost, it being stamped or struck out of thin sheet metal, and by its aid the filling of the shuttles is greatly facilitated.

Having thus described my invention, what I claim as new, and desire to secure by Letters Patent, is—

As an article of manufacture, the guide-plate A, constructed and slotted as herein shown and described, and for the purpose set forth.

ABRAM CLOW.
